(57) **CLAIM**

The ornamental design for, a child-protecting vest to be used in the vehicle, as shown and described.

DESCRIPTION

FIG. 1 is a front elevation view of a child-protecting vest to be used in the vehicle showing my new design;

FIG. 2 is a top plan view thereof;

FIG. 3 is a right side elevation view thereof;

FIG. 4 is a left side elevation view thereof;

FIG. 5 is a rear elevation view thereof;

FIG. 6 is a bottom plan view thereof; and,

FIG. 7 is a rear perspective view thereof.

The broken line showing of vehicle seat belts is for illustrative purposes only and forms no part of the claimed design.

The broken lines shown on the child-protection vest to be used in a vehicle are understood to represent stitching.
